UNITED STATES PATENT OFFICE

101,968

DESIGN FOR A BICYCLE LUGGAGE CARRIER

Ewald F. Pawsat, Maysville, Ky., assignor to Wald Manufacturing Company, Incorporated, a corporation of Kentucky

Application September 17, 1936, Serial No. 64,907

Term of patent 14 years

To all whom it may concern:

Be it known that I, Ewald F. Pawsat, a citizen of the United States, residing at Maysville, in the county of Mason and State of Kentucky, have invented a new, original, and ornamental Design for Bicycle Luggage Carriers, of which the following is a specification, reference being had to the accompanying drawing forming a part thereof.

In the drawing:

The figure is a perspective view of a bicycle luggage carrier showing my new design.

I claim:

The ornamental design for a bicycle luggage carrier, as shown.

EWALD F. PAWSAT.
